PAD THAI RICE NOODLES

Our special gluten-free Pad Thai Rice Noodles are ideal for making authentic Pad Thai. They're also fabulous in Asian stir-fries, savory noodle soups and chilled salads alike. Enjoy.

Chicken Pad Thai

• 1 pack	Pad Thai Rice Noodles	• 1/4 cup + 2 tbsp	Pad Thai Sauce
• 6 oz chicken breast		• 2 tbsp sugar
• 2 tbsp oil		• 8 oz bean sprouts
• 2 large eggs, beaten		• 2 tbsp crushed peanuts
• 4 cloves garlic, minced		• 1 tsp red pepper flakes
		• 1 tbsp coriander
		• 1 tbsp red lime wedges

Directions: Soak the Pad Thai Rice Noodles in hot water for 10 minutes or until tender. Drain and rinse under cold water and set aside. Slice the chicken breast into bite-sized pieces. Heat up a skillet with 2 tablespoons oil on medium heat. Gently pour in the beaten egg and fry until it starts to set, about 30 seconds. Flip the egg over and continue to fry until it's all set and cooked through. Use a spatula to break up the egg into small pieces. Remove from the skillet and set aside. Add the remaining oil into the skillet. Add the minced garlic and sauté until light brown. Add the chicken, cook until the surface turns white and chicken is cooked through, followed by the Pad Thai noodles. Add the Pad Thai Sauce, sugar and stir to mix well with the noodles. Add the bean sprouts and eggs and cook for 30 seconds. Top the noodles with crushed peanuts, red pepper flakes, coriander and lime wedges. Serve immediately.

Chinese Beef & Broccoli Rice Noodles

• 1 pack	Pad Thai Rice Noodles	• 1 tbsp soy sauce
• 6 oz beef tenderloin		• 2 tbsp oyster sauce
• 2 cloves garlic, minced		• 1 tbsp sugar
• 8 oz broccoli florets		• 1/4 cup water

Directions: Soak the Pad Thai Rice Noodles in hot water for 10 minutes or until tender. Drain and rinse under cold water and set aside. Slice the beef into bite-sized pieces. Heat up a skillet on medium heat and add the oil. Stir in the garlic, cook until aromatic. Add the beef, cook until the surface turns brown, followed by the broccoli florets. Stir and toss the beef and broccoli a few times, and then add the Pad Thai Noodles. Add soy sauce, oyster sauce and sugar. Stir continuously to mix well with the noodles. Cook for 1 minute. Serve immediately.
